(57) **CLAIM**

The ornamental design for a metal plate resistor, as shown and described.

DESCRIPTION

FIG. 1 is a front elevation view of a metal plate resistor, showing our new design. The rear elevation view being a mirror image thereof;

FIG. 2 is a left side elevation view thereof, the right side elevation view being a mirror image thereof;

FIG. 3 is a top plan view thereof;

FIG. 4 is a bottom plan view thereof; and,

FIG. 5 is a front, top and right side perspective view thereof.
